EXPANSIBLE CHAMBER MOTOR

Wade H. Wineman, Michigan City, Ind., assignor
to Sullivan Machinery Company, a corporation
of Massachusetts

Application December 30, 1943, Serial No. 516,140

11 Claims. (Cl. 121—151)

My invention relates to motors, and more particularly to expansible chamber motors adapted especially for operating pumps.

In oil fields where the stratum pressure is inadequate to raise the oil to the surface it is customary to provide for each well a pump and an expansible chamber motor for operating said pump through a sucker rod line. A system employing a central source of operating fluid is commonly used for delivering fluid to the pump motors at, say, a pressure from two to three hundred pounds per square inch and taking back fluid in the return lines from the motors at a pressure of, say, fifty to one hundred pounds per square inch. The pumping motor employed is usually single acting and has a fluid actuated valve mechanism for controlling the supply and discharge of operating fluid. At times, events, such as the blowing out of the pump packing or the breaking of the sucker rod line, occur to suddenly remove the load from the pump motor. It is necessary at such times that the motor be stopped. At other times it is desirable that one of the pump motors be stopped so that parts may be repaired or replaced. The valve mechanism for each motor should therefore be provided with automatic means and manual control means for effecting a stopping of the motor. Sometimes it is desirable that the strokes of the pump be shortened so as to effect an unsanding of the latter. To make this possible, the manual control for the motor valve mechanisms should be operative to effect a connection of the motor to the supply and discharge connections at will.

It is an object of my invention to provide an improved motor. It is another object of my invention to provide improved control means for a pump-operating motor. Another object of my invention is to provide an improved fluid actuated motor having associated therewith improved means for cutting off the supply of operating fluid to the motor in the event the load on the motor is suddenly removed. Still another object of my invention is to provide a fluid actuated pump-operating motor having improved means for controlling manually and automatically the supply of operating fluid to the motor. Yet another object of my invention is to provide an improved expansible - chamber - motor having improved means associated therewith for interrupting fluid supply to the motor and connecting the same continuously to exhaust, in the event the motor loses its load. Still another object is to provide an improved expansible-chamber-motor having a distributing valve mechanism normally operative automatically to control the connection of said motor to fluid supply and exhaust, and having manual control means operative at will for effecting movement of said distributing valve to its

supply or venting position. Other objects of my invention will hereinafter more fully appear.

In the accompanying drawings, in which for purposes of illustration one embodiment which my invention may assume in practice has been shown:

Fig. 1 is a front elevation of a pumping motor having my invention embodied therein.

Fig. 2 is an enlarged cross sectional view taken on the plane of the line 2—2 of Fig. 1.

Fig. 3 is a central vertical section through the lower end of the motor cylinder and its distributing valve mechanism, taken on the plane of the line 3—3 of Fig. 2.

Fig. 4 is a side elevation of the distributing valve mechanism and a portion of the lower motor head.

Fig. 5 is an enlarged vertical sectional view taken on the plane of the line 5—5 of Fig. 2.

Fig. 6 is a vertical sectional view like that of Fig. 5, but showing the distributing valve in a different position.

Fig. 7 is an enlarged sectional view taken on the plane of the line 7—7 of Fig. 5.

Figs. 8 and 9 are sectional views similar to Fig. 7, but showing parts in different positions.

Fig. 10 is an enlarged sectional view taken on the plane of the line 10—10 of Fig. 6.

Fig. 11 is an enlarged sectional view taken on the plane of the line 11—11 of Fig. 5.

Fig. 12 is an enlarged sectional view taken on the plane of the line 12—12 of Fig. 2.

In the illustrative embodiment of the invention, there is shown a pump motor, generally

designated 1, carried by suitable supporting means, a portion of which is shown at 2. The pump motor comprises a cylinder 4 having a bore 5 receiving a reciprocable piston 6 which has a piston rod 7 adapted to be connected to a

suitable pump rod or sucker rod line. Associated with the cylinder is an upper head member 8 and a lower head member 9, the head members being clamped to the ends of the cylinder by a series of tie rods 10. The lower head member 9

is provided with a valve chest, generally designated 12, housing and supporting mechanism for controlling the supply and discharge of fluid relative to the cylinder bore.

The valve chest comprises a motor fluid supply space 13 to which fluid is supplied through a supply connection 14, and an exhaust space 15 which is connected to an exhaust connection 16. The fluid supply may be at a pressure from 200 to 300 pounds per square inch, and the exhaust connection is maintained by suitable means, not shown, under a back pressure which may be within a range of 50 to 100 pounds per square inch. A passage 17 extends from a space 18, intermediate spaces 13 and 15, to the lower end 60 of the cylinder bore 5. The supply space 13

and the cylinder connected space 18 have between them a septum 19, and the exhaust space 15 and the space 18 have a septum 20 between them. A suitable valve-chamber forming element 21, having a stepped peripheral surface, is mounted in a series of bores 22, 23, 24 and 25 of progressively decreasing sizes and is provided with shoulders at 26 adapted to seat upon supporting surfaces 27, or, preferably, upon gaskets 28 at the junctions of the stepped bores. A head 29 is clamped on the valve chest 12, as by screws 30, opposite the lower end of the chamber forming element 21, and has a reduced portion 31 fitting within a bore 32 which extends throughout something more than half the length of the element 21. The element 21 fits loosely at its lower end within a bore 33 in the valve chest member so as to provide a continuous connection between the exhaust space 15 and a space 34 surrounding the reduced portion 31 of the head member 29. Passage means 35 connects the space 34 and the lower end of the bore 32. The bore 32 is connected by ports respectively numbered 36, 37 and 38 with the supply space 13, the cylinder connected space 18, and the exhaust space 15. Opening through the upper end of the element 21 is a bore 39 coaxial with the bore 32 and somewhat larger than the latter bore. An upper head 40 is held in any suitable manner, as by screws 41, in a position to close the upper end of the bore 39 and to hold the element 21 in place.

Reciprocable within the bores 32 and 39 is a distributing valve element 43 having a lower head portion 44 fitting the bore 32, an intermediate portion 45 also fitting the bore 32, a narrow annular enlarged portion 46 fitting the bore 39, and an upper longer enlarged portion 47 also fitting the bore 39. The portions 44, 45, 46 and 47 are each appropriately ringed or otherwise packed. Portions 46 and 47 are separated by a reduced portion 48 which provides a fluid conducting groove 49 whose function will be later described. Portions 44 and 45 are separated by a reduced portion 50 to provide a space 51 for selectively connecting the passage 17 with the supply and exhaust spaces in the different positions of the distributing valve. Any suitable means may be provided, if desired, such as a stop boss 52, to prevent the distributing valve 43 from making a complete surface contact between its upper end and the inner side of the head 40.

Extending longitudinally through the element 21 is a passage 55 communicating at its upper end with the top of the bore 39, and opening at its lower end into the bore 39 at a point which communicates with the groove 49 when the distributing valve is in its upper position, and which is covered by the head 47 when the distributing valve is in its lower position. A passage 58 in the element 21 opens into the bore 39 at a point uncovered by the upper end of the head 47 of the distributing valve when the latter is in its lower position, and covered by the head 47 when the valve is in its upper position. A passage 59 opens through the element 21 into the bore 39 at such a point that it is connected by the groove 49 with the passage 55 when the distributing valve is in its upper position, and is covered by the head 47 when the distributing valve is in its lower position. A vent port 60 opens into the bore 39 at the lowermost portion of the latter, and bleeds off any pressure fluid leaking along the valve 43.

Attached to the side of the element 21, as by

bolts 61, is a plate member 62 having a recess 63 which cooperates with the element to form a valve chamber 64. The passages 58 and 59 open through the outer surface of the element 21 into the chamber 64. Arranged within this chamber is a valve plate 65 connected to a pin 66 which is rotatably supported in bores 67 and 68, respectively, in the element 21 and in the plate member 62. Attached to the outer end of the pin 66 is an operating lever 70 by means of which the valve plate 65 may be rotated to any one of the positions shown in Figs. 7, 8 and 9. Formed in the inner face of the valve plate 65 are radial grooves 71 and 72, and arcuate grooves 73 and 74. Extending through the valve plate between the grooves 71, 73 and 72, 74, as shown in Fig. 7, are ports 75 and 76.

Formed in the element 21, as shown in Fig. 10, are passages 82 and 83 opening through the inner wall of the chamber 64 at points which are connected by the radial grooves 71 and 72, respectively, to the passages 58 and 59 when the valve plate 65 is in the position shown in Fig. 7. A conduit 85 connects the passage 82 with the cylinder bore 5 at a point 86 in the latter so located that it is uncovered by the upper end of the downwardly moving piston 6 only approximately as the desired lower limit of the piston stroke is reached. A conduit 87 connects the passage 83 with the cylinder bore at a point 88 so located that the upwardly moving piston passes above it only as the piston attains approximately to the desired upper limit of travel. Extending longitudinally through the element 21 is a passage 89 connecting the port 36 in communication with the inner end of the bore 67. Formed in the valve supporting pin 66 are passage means 91 opening through the inner end of the pin and communicating with the valve chamber 64 at the outer side of the valve plate 65. When the valve plate is in the position shown in Fig. 8, the ports 75 and 76 in the valve plate connect the chamber 64 at the outer side of the valve plate in communication with the passages 58 and 59. Vent passages 93 and 94 in the element 21 open through the inner wall of the chamber 64 at points communicating with the arcuate grooves 73 and 74 in all positions of the valve plate 65. When the valve plate is rotated to the position shown in Fig. 9, the passages 58 and 59 are connected through the grooves 73 and 74 to the vent passages 93 and 94.

It is evident that the valve plate 65 may be moved manually through the lever 70 to any one of the positions shown. Associated with the lever 70 are control means, generally designated 96, for moving the valve plate 65 automatically from the position shown in Fig. 7 to the position shown in Fig. 8 when certain events, shortly to be explained, take place. The control means 96 comprises, as shown in Fig. 12, a cylinder member 97 having a bore 98 containing a reciprocable plunger 99 which has a portion 100 projecting through one end of the cylinder. A spring 101 acts between the cylinder and the plunger to hold the latter normally in a retracted position. A cylinder head 102 is provided with a port 103 connecting the bore 98 in communication with a conduit 104 which opens into the bore 5 of the motor cylinder at a point above the upper end of the normal stroke of the piston 6. Attached to the cylinder 97 is a spring 105 having a bent end 106 for engaging a projecting portion 107 on the valve operating lever 70 when the valve 65 is in the position shown in Fig. 7, and acting to hold yield-

ingly the valve in such position. Fixed to the lever 70 is a projecting arm 109 adapted to engage the cylinder 97 for limiting the swinging of the lever 70 to the position shown in Fig. 9. When fluid is supplied under pressure to the bore 98, the plunger 99 is forced outwardly and actuates the lever to move the valve 65 into the position shown in Fig. 8.

The upper portion of the cylinder bore 5 is connected through a suitable automatic relief valve device 110 in communication with the atmosphere. This device is effective during normal operation of the pump motor to preclude the building up of a material back pressure against the motor piston during its upward movement, but effective largely to prevent discharge of air from above the motor piston when the latter moves upwardly faster than a predetermined maximum rate.

The operation of the mechanism described is as follows: Assuming that the valve plate 65 is in the position shown in Fig. 7, and that the distributing valve is in its fluid supplying position shown in Fig. 6, pressure fluid will then pass from the motor fluid supply chamber 13 through the port 36, the space 51 and the passage 17 to the cylinder bore 5 where it acts on the piston 6 to move the latter in an upward direction. As the piston passes above the point 86 where the conduit 85 connects to the motor cylinder, nothing happens since the passage 58 connecting the conduit 85 to the bore 39 of the distributing valve is blocked off by the head portion 47. The motor piston continues to move upwardly until the point 88 is overrun. At this time pressure fluid from beneath the motor piston passes through the conduit 87, the passage 83, the groove 72, the passage 59, the groove 49 and the passage 55 to the upper end of the bore 39 where it acts on the head portion 47 of the distributing valve, and moves the latter to its venting position, shown in Fig. 5. The space beneath the motor piston is then connected through the passage 17, port 37, the space 51 and the port 38 to the exhaust chamber 15, and since the pressure beneath the motor piston is insufficient to support the load on the latter, the piston will move downwardly in the motor cylinder bore. When the motor piston uncovers the point 88 when the conduit 87 connects to the motor cylinder, nothing happens since the passage 59 is covered at its inner end by the head portion 47 of the distributing valve. As the motor piston passes below the point 86, however, fluid will be vented from the space above the distributing valve through the passage 58, the groove 71, the passage 82, the conduit 85, and the upper portion of the cylinder bore to atmosphere through the relief valve 110. The distributing valve will then be forced upwardly due to the back pressure acting on the head portion 44, and fluid will then again be supplied to the motor cylinder to start another upward stroke of the motor piston.

If it is desired to stop the operation of the motor piston, it is only necessary to move the valve plate 65 into the position shown in Fig. 8. With the valve plate in this position, fluid is supplied from the supply chamber 13 through the port 36, passage 89, and the passage means 91 to the valve chamber 64 at the outer side of the valve plate where it flows through the ports 75 and 76 to the passages 58 and 59. If the distributing valve is in its upper position, fluid will flow from the passage 59 through the groove 49 to the passage 55 where it will be conducted to

the upper end of the head portion 47 and force the distributing valve to its lower position. With the distributing valve in its lower position, fluid will be admitted through the passage 58 to the upper end of the head portion 47 and effect a holding of the distributing valve in its exhaust effecting position. The valve plate 65 may be moved from the position shown in Fig. 7 to that shown in Fig. 8 by manual operation of the lever 70 or by actuation of the plunger 99 by fluid supplied to the latter through the conduit 104 and the passage 103. It will be seen that the passage 104 communicates with the motor cylinder at a point which is normally connected to atmosphere. In the event that the motor piston moves upwardly too fast due to a blowout of the pump packing or a rupture of the sucker rod line, the communication to atmosphere through the relief valve 110 will be largely cut off and pressure within the upper portion of the motor cylinder will be delivered through conduit 104 to the plunger 99 for moving the latter to effect actuation of the lever 70 for moving the valve plate 65 into the position shown in Fig. 8. As long as the valve plate 65 remains in the position shown in Fig. 8, the operation of the pump motor will be discontinued.

At times it may be desirable that the motor piston be caused to reciprocate in short strokes. By moving the valve plate 65 from the position shown in Fig. 8 to that shown in Fig. 9, fluid will be vented from the upper end of the head portion 47 of the distributing valve through the passages 58 and 59 to the annular grooves 73 and 74 and the vent passages 93 and 94. The distributing valve will then be moved by back pressure acting on its lower head portion 44 to its upper position for delivering pressure fluid to the motor cylinder. When the motor piston has moved upwardly the desired distance, the valve plate 65 may again be moved manually to the position shown in Fig. 8 for delivering pressure fluid to the upper end of the distributing valve and causing the latter to move to its exhaust effecting position. It will be seen that by manually adjusting the valve plate 65 to the positions shown in Figs. 8 and 9, any desired stroke of the motor piston may be obtained.

As a result of this invention there has been provided an improved pump motor. It will be noted that the operation of the motor piston may be controlled automatically or manually to discontinue its operation. The fluid supply may also be conveniently controlled to effect any desired operation of the motor piston.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a single-acting expansible chamber motor having a cylinder, a piston reciprocable in said cylinder, a fluid actuated distributing valve having a cylinder-connected throwing passage, a source of throwing pressure independent of said cylinder, venting means, and means for selectively connecting said distributing valve to said throwing passage, said independent source of throwing pressure, and said venting means.

2. In combination, a single-acting expandible chamber motor having a cylinder, a piston reciprocable in said cylinder, a fluid actuated distributing valve having a cylinder-connected throwing passage, a source of throwing pressure independent of said cylinder, and manually controlled means for switching the connection of said distributing valve from said cylinder-connected throwing passage to said independent pressure source.

3. In combination, a single-acting expandible chamber motor having a cylinder, a piston reciprocable in said cylinder, a fluid actuated distributing valve having a cylinder-connected throwing passage, a source of throwing pressure independent of said cylinder, venting means, and manually controlled means for switching the connection of said distributing valve from said cylinder-connected throwing passage to said independent pressure source or to said venting means.

4. In combination, a single-acting expandible chamber motor having a cylinder, a piston reciprocable in said cylinder, a fluid actuated distributing valve having a cylinder-connected throwing passage, a source of throwing pressure independent of said cylinder, automatic means responsive to pressure transmitted thereto upon an excessive rate of travel of said piston for switching the connection of said distributing valve from said cylinder-connected throwing passage to said independent source, and manual control means for effecting switching of the connection of said distributing valve from said cylinder-connected throwing passage to said independent source at will.

5. In combination, a single-acting expandible chamber motor having a cylinder, a piston reciprocable in said cylinder, a fluid actuated distributing valve having a cylinder-connected throwing passage, a source of throwing pressure independent of said cylinder, venting means, automatic means responsive to pressure transmitted thereto upon an excessive rate of travel of said piston for switching the connection of said distributing valve from said cylinder-connected throwing passage to said independent source, and manual control means for effecting switching at will of the connection of said distributing valve from said cylinder-connected throwing passage to said independent source or to said venting means.

6. A single-acting motor comprising a cylinder, a piston reciprocable therein, a fluid actuated distributing valve for controlling the connection of said cylinder to fluid supply and exhaust, said distributing valve moving to its exhaust effecting position on the supply of pressure fluid thereto, means including a cylinder connected throwing passage for controlling normally the flow of pressure fluid to and from said distributing valve, an independent source of pressure fluid, and manually operated means for selectively connecting said distributing valve to said throwing passage and said independent source of pressure fluid.

7. A single-acting motor comprising a cylinder, a piston reciprocable therein, a fluid actuated distributing valve for controlling the connection of said cylinder to fluid supply and exhaust, said distributing valve moving to its exhaust effecting position on the supply of pressure fluid thereto, means including a cylinder connected throwing passage for controlling normally the flow of pressure fluid to and from said distributing valve, an independent source of pressure fluid, venting means, and manually operated means for selectively connecting said distributing valve to said

throwing passage, said independent source of pressure fluid, and said venting means.

8. A single-acting motor comprising a cylinder, a piston reciprocable therein, a fluid actuated distributing valve for controlling the connection of said cylinder to fluid supply and exhaust, said distributing valve moving to its exhaust effecting position on the supply of pressure fluid thereto, means including a cylinder connected throwing passage for controlling normally the flow of pressure fluid to and from said distributing valve, an independent source of pressure fluid, automatic means responsive to pressure transmitted thereto upon an excessive rate of travel of said piston in a working direction for switching the connection of said distributing valve from said throwing passage to said independent source of pressure fluid, and manual control means for switching at will the connection of said distributing valve from said throwing passage to said independent source of pressure fluid.

9. A single-acting motor comprising a cylinder, a piston reciprocable therein, a fluid actuated distributing valve for controlling the connection of said cylinder to fluid supply and exhaust, said distributing valve moving to its exhaust effecting position on the supply of pressure fluid thereto, means including a cylinder connected throwing passage for controlling normally the flow of pressure fluid to and from said distributing valve, an independent source of pressure fluid, venting means, automatic means responsive to pressure transmitted thereto upon an excessive rate of travel of said piston in a working direction for switching the connection of said distributing valve from said throwing passage to said independent source of pressure fluid, and manual control means for switching at will the connection of said distributing valve from said throwing passage to said independent source of pressure fluid.

10. A motor comprising a cylinder, a piston reciprocable therein, a fluid actuated distributing valve for controlling the connection of said cylinder to fluid supply and exhaust, a source of fluid supply, fluid venting means, means including a valve member movable to positions for connecting said distributing valve to said fluid supply source and said venting means, means operative automatically upon an excessive rate of travel of said piston for moving said valve member to a position connecting said distributing valve to said source of fluid supply, and manual control means for moving said valve member to positions connecting said distributing valve to said source of fluid supply and said venting means at will.

11. A motor comprising a cylinder, a piston reciprocable therein, a fluid actuated distributing valve for controlling the connection of said cylinder to fluid supply and exhaust, said distributing valve operative on the supply of pressure fluid thereto for connecting said motor cylinder to exhaust, a source of fluid supply, fluid venting means, means including a valve member movable to positions for connecting said distributing valve to said fluid supply source and said venting means, means operative automatically upon an excessive rate of travel of said piston for moving said valve member to a position connecting said distributing valve for said source of fluid supply, and manual control means for moving said valve member to positions connecting said distributing valve to said source of fluid supply and said venting means at will.

CERTIFICATE OF CORRECTION.

Patent No. 2,378,965.

June 26, 1945.

WADE H. WINEMAN.

It is hereby certified that error appears in the printed specification of the above numbered patent requiring correction as follows: Page 1, second column, line 1, for the word "position" read --positions--; page 4, second column, line 70, claim 11, for "for" after "valve" read --to--; and that the said Letters Patent should be read with this correction therein that the same may conform to the record of the case in the Patent Office.

Signed and sealed this 6th day of November, A. D. 1945.
